(57) **CLAIM**

The ornamental design for a tank handling apparatus for use lifting, supporting and manipulating cylindrical tanks, as shown and described.

DESCRIPTION

FIG. 1 is a front three-quarter perspective view embodying our new design for a tank handling apparatus for use lifting, supporting and manipulating cylindrical tanks;

FIG. 2 is a front plan view thereof;

FIG. 3 is a rear plan view thereof;

FIG. 4 is a left elevational view thereof;

FIG. 5 is a right elevational view thereof;

FIG. 6 is a top plan view thereof; and,

FIG. 7 is a bottom plan view thereof.

The broken lines shown in the drawings depict environmental structure only and form no part of the claimed design.
